UNITED STATES PATENT OFFICE

92,296

DESIGN FOR A KNITTED FABRIC

Harry Gross, New York, N. Y., assignor to Concord Chenille Co., Inc., New York, N. Y., a corporation of New York

Application April 17, 1934, Serial No. 51,431

Term of patent 3½ years

To all whom it may concern:

Be it known that I, HARRY GROSS, a citizen of the United States, and resident of New York, N. Y., in the county of New York and State of New York, have invented a new, original, and ornamental Design for a Knitted Fabric, of which the following is a specification, reference being had to the accompanying drawing forming part thereof.

The figure is a plan view of a knitted fabric, showing my new design.

The solid black band at the top of the fabric represents a dark background over which the design of the fabric is illustrated. The bell-shaped elements of the fabric are convexed upwardly above the general level of the fabric.

I claim:

The ornamental design for a knitted fabric, as shown and described.

HARRY GROSS.
